United States Patent Office

Des. 178,631
Patented Sept. 4, 1956

178,631

COMBINED DIAL AND HANDS FOR TIMEPIECES

Marcel-Jacques Bloch, La Chaux de Fonds, Switzerland

Application June 9, 1955, Serial No. 36,432

Term of patent 3½ years

(Cl. D42—1)

Fig. 1.

Fig. 2.

Fig. 1 is a front elevational view of a combined dial and hands for timepieces showing my new design, and Fig. 2 is a side elevational view thereof.

The dominant features of the design reside in the portions shown in full lines.

I claim:

The ornamental design for a combined dial and hands for timepieces, as shown and described.
